[57] CLAIM

The ornamental design for a combined fly and jig box,
as shown and described.

DESCRIPTION

FIG. 1 is a perspective view of a combined fly and jig box
showing my new design in an open condition, it
being understood that the pattern of cylindrical pegs is
continuous along the path of the dashed lines;

FIG. 2 is a top plan view thereof, the bottom surfaces
being plain and unornamented;

FIG. 3 is a side elevational view thereof; and

FIG. 4 is an end elevational view thereof.
